UNITED STATES PATENT OFFICE.

ALEXANDER D. CUNNY, OF CINCINNATI, OHIO, ASSIGNOR TO O. P. SCHRIVER & CO., OF SAME PLACE.

DESIGN FOR A SASH-BALANCE HOUSING.

SPECIFICATION forming part of Design No. 30,413, dated March 28, 1899.

Application filed February 27, 1899. Serial No. 707,113. Term of patent 7 years.

To all whom it may concern:

Be it known that I, ALEXANDER D. CUNNY, a citizen of the United States, residing at Cincinnati, in the county of Hamilton and State of Ohio, have invented and produced a new and original Design for a Sash-Balance Housing; and I do hereby declare the following to be a full, clear, and exact description of the same, reference being had to the accompanying drawings, forming a part thereof.

In said drawings, Figure 1 is a plan of a sash-balance housing embodying my design. Fig. 2 is a side elevation of said ornamented housing.

15 The aforesaid housing includes a flat base-plate A and a cap B, which cap has the angular shape shown in Fig. 2. The opposite

edges of the central portion of the cap have beads or moldings C C', that take the shape of annular segments, and said beads are continued down the ends of said cap, as at c c'. These continuations of the beads are straight, not curved. Again, the housing A B has eyes D D', surrounded with radial beads or swells d d', having rounded outer ends. 25

I claim as my invention—

The design for a sash-balance housing, as herein shown and described.

In testimony whereof I affix my signature in presence of two witnesses.

ALEXANDER D. CUNNY.

Witnesses:

JAMES H. LAYMAN,
JESSE M. SIMON.
